CLAIM

The ornamental design for an apparatus for thermotherapy as shown and described.

DESCRIPTION

1. Apparatus for thermotherapy

1.1 : Perspective

1.2 : Front

1.3 : Back

1.4 : Left

1.5 : Right

1.6 : Top

1.7 : Bottom

Fig. 1.1 is a perspective view of an apparatus for thermotherapy in accordance with the present design; Fig. 1.2 is a front view thereof; Fig. 1.3 is a rear view thereof; Fig. 1.4 is a left side view thereof; Fig. 1.5 is a right side view thereof; Fig. 1.6 is a top view thereof; Fig. 1.7 is a bottom view thereof; and, the dashed broken lines depict portions of the apparatus for thermotherapy that form no part of the claimed design.
